UNITED STATES PATENT OFFICE

169,374

AIR REGISTER GRILLE

Frank C. Kiesner, St. Paul, Minn.

Application May 26, 1952, Serial No. 19,898

Term of patent 3½ years

(Cl. D81—21)

To all whom it may concern:

Be it known that I, Frank C. Kiesner, a citizen of the United States, residing in St. Paul, county of Ramsey, and State of Minnesota, have invented a new, original, and ornamental Design for an Air Register Grille, for which the following is a specification, reference being had to the accompanying drawing forming part thereof:

I claim:

The ornamental design for an air register grille, as shown.

FRANK C. KIESNER.
